UNITED STATES PATENT OFFICE.

JOHN CRAIGHTON, OF DEER LODGE, MONTANA.

TORCH FOR IGNITING BLAST-FUSES.

No. 893,309.

Specification of Letters Patent.

Patented July 14, 1908.

Application filed September 16, 1907. Serial No. 393,037.

To all whom it may concern:

Be it known that I, JOHN CRAIGHTON, a citizen of the United States, residing at Deer Lodge, in the county of Powell and State of Montana, have invented certain new and useful Improvements in Torches for Igniting Blast-Fuses, of which the following is a specification, reference being had to the accompanying drawings.

10 My invention relates to improvements in devices for firing explosives and more particularly to a torch or igniting device by means of which fuses of a plurality of charges of explosive material may be successively ignited in a safe and expeditious manner.

The object of the invention is to provide a device of this character which will be simple, inexpensive and highly effective for the purpose intended.

20 With the above and other objects in view the invention consists of the features of novelty hereinafter described and claimed and illustrated in the accompanying drawings in which

25 Figure 1 is a perspective view of a torch or igniting device constructed in accordance with my invention; Fig. 2 is a longitudinal section; and Fig. 3 is a diagrammatic view illustrating a plurality of explosive charges 30 and their fuses which latter the invention is especially designed to ignite.

My improved torch or igniting device consists of a combustible member 1 and a holder or handle 2 for the same. The member 1 is in 35 the form of a band of tape or fabric impregnated or coated with a highly combustible substance such as salt peter, and I preferably make it from an ordinary lamp-wick by soaking the same in a solution of water and salt 40 peter and then allowing it to dry. The holder 2 is in the form of a straight rod having one of its ends bent to provide a hand piece 3 and its other end tapered to a point 4 so that it may be readily passed through the 45 torch body or member 1 one or more times as illustrated in the drawings.

In Fig. 3 of the drawings is shown a plurality of charges of dynamite or other blasting powder arranged in the rock or earth E 50 which is to be blasted and provided with the usual fuses F which are to be successively ignited and which are therefore of successively decreasing length from the first to the last charge. The usual practice in igniting a series of charges of this kind is to take a candle and successively ignite the ends of the

fuses F beginning with the longest fuse. It frequently happens that the first or second fuse in being ignited sputters and causes the candle to be extinguished and that before the 60 candle can be relighted and the remaining fuses can be ignited the first fuse has burned to the charge and the latter goes off. My improved torch or igniting device above described is so constructed that it cannot be 65 extinguished by the sputtering of the fuses and may be effectively used to successively ignite the fuses of the several charges. When the body or member 1 of the torch is once ignited it cannot be blown out and it 70 burns with sufficient power to enable the several fuses to be quickly and effectively ignited. The use of the invention entirely obviates the liability of the first charge of a series exploding before the fuse of the last 75 one has been ignited.

Having thus described my invention what I claim is:

1. As an article of manufacture, a torch for igniting blast fuses, comprising a holder in 80 the form of a rod bent at one end to provide a hand loop and having its other end pointed and passed a plurality of times through a flexible torch bent or folded back and forth upon itself, substantially as shown and de- 85 scribed.

2. As an article of manufacture, a torch for igniting blast fuses, comprising a holder in the form of a rod bent at one end to provide a hand loop and having its other end pointed 90 and passed a plurality of times through a torch in the form of a strip of flexible material containing a combustible substance, said torch being folded back and forth upon itself a plurality of times, substantially as 95 shown and described.

3. As an article of manufacture, a torch for igniting blast fuses, comprising a holder in the form of a rod bent at one end to provide a hand loop and having its other end pointed 100 and passed a plurality of times through a torch in the form of a strip of fabric impregnated with a highly combustible substance, said torch being bent or folded back and forth upon itself a plurality of times, sub- 105 stantially as shown and described.

In testimony whereof I hereunto affix my signature in the presence of two witnesses.

JOHN CRAIGHTON.

Witnesses:

WARNER E. EVANS,
JEROME P. WYCKOFF.
